UNITED STATES PATENT OFFICE

ODE D. JENNINGS, OF CHICAGO, ILLINOIS, ASSIGNOR TO O. D. JENNINGS & COMPANY, OF CHICAGO, ILLINOIS, A CORPORATION OF ILLINOIS

DESIGN FOR A CASING FOR A WEIGHING AND VENDING MACHINE

Application filed June 13, 1930. Serial No. 36,036. Term of patent 7 years.

To all whom it may concern:

Be it known that I, ODE D. JENNINGS, a citizen of the United States, residing at Chicago, in the county of Cook and State of Illinois, have invented a new, original, and ornamental Design for a Casing for a Weighing and Vending Machine, of which the following is a specification, reference being had to the accompanying drawing, forming part thereof, in which the figure is a perspective view of a casing for a weighing and vending machine showing my new design.

I claim:

The ornamental design for a casing for a weighing and vending machine, substantially as shown.

ODE D. JENNINGS.
